CLAIM

The ornamental design for a lighted dishwasher door, as shown and described.

DESCRIPTION

FIG. 1 is a perspective view of a light for a dishwasher door according to a first embodiment showing our new ornamental design;

FIG. 2 is a top view thereof;

FIG. 3 is a front view thereof;

FIG. 4 is a right side view thereof; and,

FIG. 5 is a left side view thereof.

The broken lines of the dishwasher, door and/or components thereof show surrounding structure or environment and do not form part of the claimed design.

The dotted lines represent the border between claimed and unclaimed subject matter and do not form a part of the claimed design.

The rear of the dishwasher door, and the bottom, sides, rear and/or top of the dishwasher are unornamented or simply not claimed and form no part of the claimed design.
